H. L. HEITER

CONTAINER

Filed Sept. 14, 1922

Fig. 4.

Inventor
Henry L. Heiter

By J. F. and J. F. Freeman
his Attorney

UNITED STATES PATENT OFFICE.

HENRY L. HEITER, OF BROOKLYN, NEW YORK.

CONTAINER.

Application filed September 14, 1922. Serial No. 588,134.

My invention relates to containers and refers particularly to devices capable of use with a plurality of toilet powder compacts.

In order that a container of the class to which my device is directed may have its highest efficiency, it must be capable of carrying a plurality of toilet powder compacts, must be compact in form, must have the proper arrangement of mirrors, must be easy of operation and must be of such construction that it will not be affected or injured by repeated use.

The container of my invention possesses all of these advantages and others which will be evident upon a consideration of the accompanying drawings and specification.

By means of the particular arrangement of parts of my device, I am able to present a container without loss of interior space, thus producing a most compact device, while containing a plurality of different powder compacts, a plurality of powder puffs and a plurality of mirrors, all arranged for their most practical and efficient employment.

In the accompanying drawings, illustrating one form of the device of my invention, similar parts are designated by similar numerals.

Figure 1 is a perspective view of one form of my device in closed position.

Figure 2 is a top plan view of Figure 1 with the top and bottom in open position.

Figure 3 is a top plan view of Figure 1 with the top, bottom and mirror carrier in open position.

Figure 4 is a section through the line 4—4 of Figure 1.

The particular container of my invention, shown in the accompanying drawings, comprises a bottom 10 having a peripheral upwardly extended flange 11, the upper portion of which is slightly inset at 12 and carries the extended catch member 13.

Hingedly attached to the bottom flange 11 at 14 is a top 15 having a peripherally extended flange 16 capable of telescopic placement over the inset 12 of the bottom member, the catch member 17 coacting with the catch member 13 to prevent the accidental opening of the container. The central portion of the top 15 is domed outwardly at 18.

Fixedly carried by the top is an annular member 19, 20, 21, 22, 23 formed as shown, and having the central annular opening 24, the member 22 having an opening 25 therein.

Hingedly attached at 26 to one side of the annular element 22 is an annular mirror carrying member comprising the annular element 27 having an annular opening 28 and the annular opening 31 and carrying the finger catch 32. A catch member 33, carried by the element 29, is capable of placement through the opening 24 of the member 22, when the device is in closed position, to prevent accidental movement of the mirror carrying member. The angular formation of the mirror carrying member formed by the elements 29, 30 fits snugly within the angular space of the top formed by the elements 21, 22. A fixed guard plate 34 prevents the displacement of the hinge 26.

Mirrors 35 and 36 are carried by the mirror carrying member.

An annular face powder compact 37, preferably white, is affixed to the annular supporting plate 38, which, in turn, is affixed to the inner face of the bottom 10 by means of cementitious material 39.

An annular face powder compact 40, preferably rouge, is affixed to the annular supporting plate 41, which, in turn, is affixed to the top dome 18 by means of cementitious material 42.

Powder puffs 43 and 44 are loosely carried by the container.

In operation, the container is opened by revolving the top upwardly from the bottom upon the hinge 14, thus exposing the powder puff 43, the white powder compact 37 and the mirror 36. When it is desired to employ the rouge, the mirror container is revolved around the hinge 26, thus exposing the powder puff 44, the rouge 40 and the mirror 35.

An examination of the drawings, and particularly Figure 4, illustrates the compactness of the device and the efficiency employment of the inside area for the purposes for which it is designed.

As all of the parts, with the exception of the powder puffs, are strongly and fixedly attached to each other, the device is capable of receiving repeated use without the danger of injury incident thereto, and the arrangement of the mirrors is such that one or the other is presented in proper position for use with each of the powder compacts.

My device, therefore, presents a new, novel and useful means for the economic and efficient accomplishment of the desired results.

I do not limit myself to the particular size, shape, number or arrangement of parts, as shown in the drawings, and described, as these are given simply as a means for the 5 clear description of my invention.

What I claim is:—

1. In a powder compact container, in combination, a bottom, a top hingedly attached to the bottom, an annular member within the 10 top and spaced from the top, an opening within the annular member, a mirror-carrying member hingedly attached to the annular member and oppositely exposed mirrors carried by the mirror-carrying member.
- 15 2. In a powder compact container, in combination, a bottom having an upwardly extended flange, the upper portion of which is offset, a top hingedly attached to the bottom and having an extended annular flange, an 20 annular member within the top spaced from the inner face of the top and from the top flange to allow of the telescopic positioning of the top flange and the bottom flange, a comparatively small opening within the annular member opening into the space between the annular member and the top, a mirror carrier hingedly attached to the annular member of smaller diameter than the top and oppositely exposed mirrors carried 25 by the mirror carrier.
- 30 3. In a powder compact container, in combination, a bottom having an upwardly extended flange, the upper portion of which is offset, a top hingedly attached to the bottom and having an extended annular flange, an 35 annular member within the top spaced from the inner face of the top and from the top flange to allow of the telescopic positioning of the top flange and the bottom flange, a comparatively small opening within the annular member opening into the space between the annular member and the top, a mirror carrier of smaller diameter than the top hingedly attached to the annular member so positioned that a mirror carried by the mirror carrier can be inserted within the opening of the annular member and oppositely exposed mirrors carried by the mirror carrier.
- 40 4. In a powder compact container, in combination, a bottom having an upwardly extended flange, the upper portion of which is offset, a top hingedly attached to the bottom and having an extended annular flange, an 45 annular member within the top spaced from the inner face of the top and from the top flange to allow of the telescopic positioning of the top flange and the bottom flange, a comparatively small opening within the annular member opening into the space between the annular member and the top, a mirror carrier of smaller diameter than the top hingedly attached to the annular member so positioned that a mirror carried by the mirror carrier can be inserted within the opening of the annular member and oppositely exposed mirrors carried by the mirror carrier.
- 50 5. In a powder compact container, in combination, a bottom having an upwardly extended flange, the upper portion of which is offset, a top hingedly attached to the bottom and having an extended annular flange, an 55 annular member within the top spaced from the inner face of the top and from the top flange to allow of the telescopic positioning of the top flange and the bottom flange,

flange, a comparatively small opening within the annular member opening into the space between the annular member and the top, a mirror carrier of smaller diameter than the top hingedly attached to the annular member so positioned that a mirror carried by the mirror carrier can be inserted within the opening of the annular member, the mirror carrier when closed not extending beyond the top flange.

6. In a powder compact container, in combination, a bottom, a top having an annular side flange hingedly attached to the bottom, an annular member carried by and within the top and spaced from the top, a comparatively small opening in the annular member, a mirror carrier of smaller diameter than the top hingedly attached to the device, a mirror capable of insertion within the annular opening carried by the mirror carrier and a larger mirror carried by the opposite side of the mirror carrier.

7. In a powder compact container, in combination, a bottom capable of containing a powder compact having an upwardly extended side flange, a top having an annular side flange hingedly attached to the bottom, an annular member carried by and within the top and spaced from the top, forming a space capable of containing a second smaller powder compact, a comparatively small opening in the annular member, a hingedly attached mirror carrier of smaller diameter than the top, a mirror capable of insertion within the annular opening carried by the mirror carrier and a larger mirror carried by the opposite side of the mirror carrier.

8. In a powder compact container, in combination, a bottom capable of containing a powder compact having an upwardly extended side flange, a top having an annular side flange hingedly attached to the bottom, an annular member carried by and within the top and spaced from the domed top, forming a space capable of containing a second smaller powder compact, a comparatively small opening in the annular member, a mirror carrier of smaller diameter than the top hingedly attached to the top, approximately opposite the top and bottom hinge, a mirror capable of insertion within the annular opening carried by the mirror carrier and a larger mirror carried by the opposite side of the mirror carrier.

Signed at New York city, in the county of New York and State of New York, this 13th day of September, 1922.

HENRY L. HEITER.
